UNITED STATES PATENT OFFICE.

DAVID L. CROSS, OF AUSTIN, TEXAS.

ROTARY STEAM-ENGINE.

SPECIFICATION forming part of Letters Patent No. 244,558, dated July 19, 1881.

Application filed April 7, 1881. (No model.)

To all whom it may concern:

Be it known that I, DAVID L. CROSS, a citizen of the United States, residing at Austin, in the county of Travis and State of Texas, have invented certain new and useful Improvements in Rotary Steam-Engines; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

15 My invention relates to improvements in rotary steam-engines; and the objects of my improvements are, first, to provide a novel form of valve for regulating the induction and eduction of steam to and from the cylinder; second, to provide novel devices for reversing the movements of the rotating pistons; and, third, to provide novel combinations of the parts of which the engine is composed. I accomplish these objects by the mechanism illustrated in 25 the accompanying drawings, in which—

Figure 1 is a side elevation of an engine, showing a base upon which the parts rest, the cylinder in which the pistons move, an eccentric for moving the valves, a slide and arm for communicating motion to the valves, and one of the steam-chests. Fig. 2 is a vertical section on line *x x* of Fig. 1, showing the main or driving shaft, the revolving head, the abutments for the steam to press against, the sliding pistons, the steam-chests, the passages for the steam, and the valves, together with the mechanism which moves them. Fig. 3 is a transverse section on line *y y* of Fig. 2, showing the revolving head, one of the sliding pistons, a guard for operating the piston, a spring for forcing the piston into the head, the steam-abutment, and induction and eduction openings. Fig. 4 is an elevation on line *z z* of Fig. 3, showing the valves, the steam-chests, and the steam-passages; and Fig. 5 is a detached perspective view, showing one of the valves and a portion of the shaft to which it is secured.

Similar letters refer to similar parts in the several figures.

50 In constructing engines of this type I provide a base, *A*, of the required dimensions and

of the form required for supporting the parts of the engine. Upon the base *A* there is placed a seat, *A'*, in which are formed induction and eduction passages for steam. This seat may 55 be separate from the cylinder *A²*, or it may constitute a part thereof, as preferred, it being shown as a part of said cylinder. The cylinder *A²*, just referred to, may be of any desired diameter and length, and be provided with 60 suitable heads, as shown, its proportions varying as the power to be derived from it is greater or less.

Within the cylinder *A²* there is placed a revolving head, *B*, the central and end portions 65 of which are of such diameter as to cause them to fit handsomely the interior of the cylinder.

Between the central portion, *B'*, and the outer portions, *B²* and *B³*, annular grooves or recesses *B⁴* are formed, which may be of any 70 desired depth, they forming the spaces in which the steam acts upon the sliding pistons *B⁵* and *B⁶*, said pistons moving inward and outward in radial recesses formed in the head *B*, as shown in Figs. 2 and 3. This head is carried 75 upon a shaft, *B⁷*, which passes through the center of cylinder *A*, and has one of its ends supported in a standard, *B⁸*, which may rest upon the base of the engine or upon any other suitable support, its opposite end being supported 80 by a similar standard and revolving in a plate, *B⁹*, on the opposite end of the machine.

The grooves or recesses *B⁴* of the cylinder are each provided in their lower portions with abutments *C C'*, the sliding pistons *B⁵* and *B⁶* 85 being so arranged that when either piston is passing its abutment the other one is opposite its abutment.

For the purpose of causing the pistons to be forced into the revolving head at the time 90 when they are passing the abutments they are each provided upon one of their edges with a roller, *C²*, which, just before the piston reaches the abutment, comes in contact with a curved surface formed on a guard, *C³*, the effect of 95 which is to cause the pistons to recede into the revolving head and allow them to pass the abutment without coming in contact therewith, after which they are again forced out into contact with the cylinder by means of the coiled springs *C⁴*, one of the ends of which is secured 100 to the hub of the revolving head and the other

made to rest against a shoulder formed on the sliding pistons; or the pistons may be forced into the heads by the abutments themselves in the usual manner, said abutments being made 5 with beveled or sloping ends for that purpose.

Underneath the cylinder A there are arranged two valves, D and D', they being mounted upon and moved by a shaft, D², one end of which extends out through one of the steam-chests and carries upon its outer end an arm, D⁵, for a purpose soon to be described. These valves are circular in form, and have in their inner faces steam-passages, as shown in Fig. 5, their office being to reverse the movements of 15 the revolving head and its pistons, and thus enable the operator to cause said head to revolve in either direction, as desired, and at the same time control the ingress and egress of steam to the cylinder. The movements of these 20 valves are controlled by an eccentric, E, carried upon the shaft B⁷ and located outside of the cylinder A, as shown in Fig. 2.

For the purpose of communicating the requisite movement to the valves there is provided a sliding plate, E', which is used in connection with the eccentric E, it being supported by and moving in guides E² and E³, which are secured to the head of the cylinder A. This plate has upon its inner face two projections, 30 E⁴, which bear upon the periphery of the eccentric, and thus cause a reciprocating movement of said plate as the eccentric is revolved. The plate is extended downward, as shown in Fig. 1, and has formed in it three slots, E⁵, E⁶, and E⁷, into which there enters a pin or stud, F, carried upon the arm D³, it being held in its innermost position by a spring, F', arranged upon the arm.

For the purpose of withdrawing the pin so as to place it in another slot there is attached to the outer surface of arm D³ a stand, F², of any suitable construction, to which is pivoted a bell-crank lever, F³, the inner or upper arm of which is made to grasp the pin or stud F, so 45 that by pressing down upon the horizontal arm said pin or stud will be withdrawn from the plate, and may be placed in the opposite outward slot, the effect of which will be to reverse the movements of the revolving head, or, in other

words, to cause it to revolve in the opposite 50 direction from that in which it did when the pin was in the position shown in Fig. 1.

If it is desired to prevent steam from entering the cylinder, it can be done by placing the stud or pin F in the central slot E⁶, when the 55 valves will cover the passages and prevent the entrance of steam thereto.

Outside of the valves there are formed steam-chests G and G', into which steam enters through passages G² and G³, as indicated in 60 Fig. 4, and from which it passes through the passages G⁴ in the valves and a passage, G⁵, in the base of the cylinder to the grooves or recesses formed in the revolving head, as indicated by the left-hand arrow in Fig. 3, it following the pistons in their movements throughout an entire revolution thereof, except just at the time when they are passing the abutments C C', when it passes out through the opening, as indicated by the right-hand arrow in Fig. 3, 70 it passing on its way out through the segmental opening G⁷ in the valves D.

Having thus described my invention, what I claim, and desire to secure by Letters Patent, is—

1. In a rotary engine, the sliding plate E', provided with a bearing-surface for the eccentric to act upon and with slots for the purpose of receiving a pin, in combination with the arm D³ and locking and unlocking device, substantially as shown and described, and for the purpose set forth.

2. The combination of the arm D, carrying upon its outer face the locking and unlocking device, the plate E', and the operating-valves, 85 the arrangement of the parts being substantially as shown and described.

3. The combination of the disk-valves D D', the shaft D², the arm D³, the slide E', and the eccentric E, the parts being arranged for joint 90 operation, substantially as described.

In testimony whereof I affix my signature in presence of two witnesses.

DAVID L. CROSS.
